COLLAPSIBLE OR PINLESS CLOTHESLINE

Filed Sept. 5, 1928

Inventor

J. A. Shook

Attorney

Watson E. Coleman

UNITED STATES PATENT OFFICE.

JOHN A. SHOOK, OF TRAMMEL, VIRGINIA, ASSIGNOR OF ONE-THIRD TO AUBURN W. COMPTON AND ONE-THIRD TO CHARLES A. COWDEN, BOTH OF TRAMMEL, VIRGINIA.

COLLAPSIBLE OR PINLESS CLOTHESLINE.

Application filed September 5, 1928. Serial No. 304,032.

This invention relates to the class of clothes lines and pertains particularly to a clothes line designed to be used without pins or other fastening elements to hold articles 5 of clothing thereon.

The primary object of this invention is to provide a clothes line so designed that articles of clothing will be securely held without fasteners and in addition to this of such 10 character that an increase in weight applied to the line will cause the articles carried thereby to be more tightly gripped.

Another object of the invention is to provide a clothes line formed of a series of metal 15 links each of simple construction and so designed that an article of clothing may be firmly gripped thereby and held by the flexing of one portion thereof as a result of the weight applied thereto against another portion, the article of clothing being arranged 20 between the said portions.

The invention will be best understood from a consideration of the following detailed description taken in connection with the accompanying drawing forming part of this 25 specification, with the understanding, however, that the invention is not confined to any strict conformity with the showing of the drawing but may be changed or modified 30 so long as such changes or modifications mark no material departure from the salient features of the invention as expressed in the appended claims.

In the drawing:—

Figure 1 is an elevation of a portion of a clothes line constructed in accordance with my invention;

Figure 2 is an enlarged plan view of one of the sections.

Referring to the drawing in detail there is shown a line of the character embodying the present invention, the same being indicated generally by the numeral 1.

As shown, this line is made up of a series 45 of link bodies, each indicated generally by the numeral 2, each of these bodies comprising a relatively long shank portion 3 coiled intermediate its ends to provide the loop or eye 4. At one end the shank 3 is turned back 50 upon itself to form the hook 5 while the other end is looped to form the end eye 6, this end eye being arranged vertically while the hook

5 at the opposite end is normally arranged in horizontal position.

The material of the link is continued from 55 the loop 6 forming the relatively large and normally depending loop 7 which terminates at one side in the laterally directed shank 8 normally extending longitudinally and in close proximity to the under side of the shank 60 3 between the loops 4 and 6, terminating in the hook 9 which engages through the loop 4 forming the intermediate ends of the shank 3.

When the line embodying the present invention is in use, an article or articles to be suspended therefrom has a portion thereof extended through the large depending loop 7 of a link and this portion is then moved longitudinally of the link to force it between 70 the upper and lower shanks 3 and 8 respectively. The proximity of the upper and lower shanks 3 and 8 is such that the thinnest of articles may be securely held, however, when weight is placed upon a link the pull 75 down thereon will be exerted chiefly upon the loop 4, thus causing the upper shank to bend downwardly intermediate its ends and bind the material tightly against the underlying shank 8. From this it will be readily seen 80 that the application of articles to the line will act to cause the links to more tightly grip the same.

It will be appreciated from the foregoing that a line constructed in accordance with the present invention may be inexpensively 85 manufactured and used with minimum of trouble as fastening elements such as the usual clothes pins are unnecessary.

Having thus described my invention what 90 I claim is:—

1. A clothes line of the character described, consisting of a series of links each comprising a relatively long shank having one end formed to provide a relatively large 95 loop projecting outwardly therefrom adjacent one end thereof, one end of said loop being extended to provide a second shank lying substantially parallel with the first-mentioned shank on the same side thereof as 100 the loop and connected thereto intermediate the ends thereof.

2. A clothes line of the character described, consisting of a series of loosely connected

links each comprising a relatively long shank looped intermediate its ends to form an eye, one end of said shank being formed to provide an eye and extended outwardly therefrom to set up a relatively large loop, said large loop having the side opposite the attached eye extended to form a short shank lying adjacent the central portion of and in

close proximity to the first-mentioned shank on the same side thereof as the loop and having hook connection at its end in the first-mentioned eye. ¹⁰

In testimony whereof I hereunto affix my signature.

JOHN A. SHOOK.
